UNITED STATES PATENT OFFICE

141,504

DESIGN FOR A COAT DRESS OR SIMILAR ARTICLE

Louis Raab and Jack Harmell, Los Angeles, Calif.

Application December 19, 1944, Serial No. 117,000

Term of patent 7 years

(Cl. D3—26)

To all whom it may concern:

Be it known that we, Louis Raab and Jack Harmell, citizens of the United States of America, residing at Los Angeles, in the county of Los Angeles, State of California, have invented a new, original, and ornamental Design for a Coat Dress or Similar Article, of which the following is a specification, reference being had to the accompanying drawing, forming a part thereof.

Fig. 1 is a front elevational view of a coat dress or similar article in closed position, showing our new design;

Fig. 2 is a rear elevational view of the same; and

Fig. 3 is a front elevational view similar to Fig. 1 but with the garment partially unbuttoned and opened.

We claim:

The ornamental design for coat dress or similar article, substantially as shown and described.

LOUIS RAAB.
JACK HARMELL.
